UNITED STATES PATENT OFFICE.

EUGENE B. CROCKER, OF PAWTUCKET, RHODE ISLAND.

DESIGN FOR AN EASEL.

SPECIFICATION forming part of Design No. 17,066, dated January 18, 1887.

Application filed September 9, 1886. Serial No. 213,172. Term of patent 7 years.

To all whom it may concern:

Be it known that I, EUGENE B. CROCKER, of the city of Pawtucket, in the county of Providence and State of Rhode Island, have 5 invented and produced a new and original Design for Easels, of which the following is a full, clear, and exact description, reference being had to the accompanying drawing, forming part of this specification.

10 In the drawing the illustration represents a front elevation of my newly-designed easel, shown as opened and standing and as holding a card, C, represented in broken lines.

15 The essential and characteristic feature of my design consists in the standards or rod-supports of the easel, made in representation of the foliage or leaves, flowers, and branches or stalks of the daisy plant, or the species *Bellis perennis* of the genus *Bellis*.

20 The drawing shows the standards or rod-supports S of the easel arranged to cross each other above the center of length of the standards. The free upper ends of the standards are each provided with the representation, D, 25 of the flower of the daisy plant, looking outwardly from the front of the easel, and L are representations of the leaves of the plant. The bodies of the standards represent the branches

or stalks of the plant, and the combined effect is that of the foliage of the daisy plant. 30

It is my intention to construct the design in representation of the flowers and branches alone or in representation of the entire foliage of the daisy plant, the foliage comprising the leaves, flowers, and branches or stalks of the 35 plant.

I show the central standard as provided with a second daisy flower, D', shown in broken lines, since the number of the representations of the flower upon each standard may be one 40 or more, if preferred, and still be within my design. The number of standards used may also be varied without departing from the scope of the design herein shown and described.

Having thus described my new and original 45 design, I claim as new and desire to secure by Letters Patent—

A design for an easel, substantially as herein shown and described, the same consisting in the standards or rod-supports of the easel constructed in representation of a daisy plant. 50

EUGENE B. CROCKER.
